DEAERATION PLATE FOR SOLID FUEL PROPELLANTS

Robert H. Oeinck, Sr., Huntsville, Ala., assignor to
Thiokol Chemical Corporation, Bristol, Pa., a corpora-
tion of Delaware

Filed June 22, 1962, Ser. No. 70,655

Term of patent 14 years

(Cl. D71—1)

Fig. 1

Fig. 2

FIGURE 1 is a top plan view of a deaeration plate for solid fuel propellants showing my new design, and

FIGURE 2 is a side elevational view.

The bottom, not shown, is substantially plain.

I claim:

The ornamental design for a deaeration plate for solid fuel propellants, as shown and described.
